UNITED STATES PATENT OFFICE.

FREDERICK H. M. HART, OF POUGHKEEPSIE, NEW YORK, ASSIGNOR TO J. R. SHORT MILLING COMPANY, A CORPORATION OF ILLINOIS.

QUICKLY-DETACHABLE CONNECTION BETWEEN MEMBERS AND SUPPORTING SHAFTS.

Application filed December 16, 1922 Serial No. 607,457.

To all whom it may concern:

Be it known that I, FREDERICK H. M. HART, a citizen of the United States, residing at Poughkeepsie, county of Dutchess, 5 State of New York, have invented a certain new and useful Improvement in Quickly-Detachable Connections Between Members and Supporting Shafts, and declare the following to be a full, clear, and exact description of the same, such as will enable others skilled in the art to which it pertains to make and use the same, reference being had to the accompanying drawing, which forms a part of this specification.

15 It is often necessary or desirable to remove a brush and agitator, or other element rotatable with a supporting shaft, for the purpose of cleaning, repair or replacement, without disturbing the shaft.

20 The object of the present invention is to produce a simple and novel means for attaching such an element to a shaft in such a manner that it may quickly and easily be secured in place, remain firmly locked to 25 the shaft after being attached thereto, and be readily removable or detachable when it is desired to disconnect the same from the shaft.

The various features of novelty whereby 30 my invention is characterized will herein-after be pointed out with particularity in the claims; but for a full understanding of my invention and of its objects and advantages reference may be had to the following 35 detailed description taken in connection with the accompanying drawing, wherein:

Figure 1 is an elevation of a fragment of a shaft supporting an agitator and a brush fastened thereto in accordance with the 40 present invention;

Fig. 2 is a top plan view of the devices shown in Fig. 1, one end of the locking element or bar being broken away;

Fig. 3 is an end view of the devices shown 45 in Fig. 1;

Fig. 4 is a perspective view of one end of the locking element or bar;

Fig. 5 is a perspective view of a fragment 50 of the supporting shaft, adjacent to one of the notches therein; and

Fig. 6 is a sectional view of a modified form of brush or feeding device.

Referring to the drawing, 1 and 2 represent end pieces and 3 and 4 the sides of a 55 rectangular frame. Each end piece has at

the middle thereof an ear 5 projecting at right angles to the plane of the frame and provided with a slot 6 extending lengthwise thereof. A brush 7 or other feeding device is adjustably attached to the ears by means of holding screws 8 passing through the feeding device and the slots in the ears. On the opposite side of each of the frame members 1 and 2, from that on which the ear 5 is located, is an open seat 9 coaxial with the corresponding seat at the other end of the frame and adapted to receive a supporting shaft 10. At opposite sides of each of the seats and preferably formed integral with the corresponding frame member are upwardly-projecting lugs 11; these lugs being undercut, that is, provided with notches 12, in their inner sides or edges. In other words, each pair of lugs is provided with over-hanging shoulders or undercut portions, facing the other lugs. The shaft has sections cut away in one side thereof to form two notches 13 spaced apart a distance equal approximately to the length of the frame; the depth of the notches being preferably such that the flattened surfaces produced thereby on the shaft do not lie below the plane of those portions 14 on the upper surface of the end members of the frame lying adjacent to the bearings or seats beyond the inner edges of the lugs.

The frame and the shaft are locked together by a simple detachable locking element consisting of a long strip 15 of spring metal having at the ends enlargements or heads which may conveniently take the form of flat rectangular blocks 16. The parts are so proportioned that when the locking element is placed between the lugs at opposite ends of the frame, the heads or blocks will fit into the notches or undercut portions of the lugs; and, if the shaft is resting in the seats in the frame with the notches directed outwardly and lying at the inner end of each seat, the heads on the locking element will rest within the notches in the shaft as well as in the notches or undercuts in the lugs, and thus lock the frame upon the shaft. My improved arrangement not only serves to lock the frame to the shaft so as to keep it from rotating thereon or dropping therefrom in a radial direction, but it also locks the frame and the shaft together against relative movements in the direction of the length of the shaft.

By making the body of the locking element out of spring metal, the locking element may be placed in position or be removed by the mere act of flexing the spring member so as to draw the heads or keys at the ends thereof towards each other, thus permitting the heads or keys to be detached from the notches in the lugs or to be brought into registration with such notches so as to 5 be in position to enter the same when the spring member is straightened.

Midway between the ends of the spring locking strip I have arranged a U-shaped clip 17 of spring metal, which is adapted to 10 be pressed over and grip the shaft when the parts are assembled and the locking element is in its locking portion.

In Fig. 6 I have shown a modified form 15 of brush or feeding device, the same consisting of a strip of leather 18 clamped between two thin bars or plates 19 of metal; the clamping plates in the leather being held together by means of suitable holding screws 20 passing through the clamping plates and 25 through elongated slots 21 in the leather. The slots permit the leather to be adjusted relatively to the clamping and holding plates as wear occurs.

It will thus be seen that I have produced 30 a simple and effective means for detachably locking a member to a supporting shaft so that it may quickly and easily be removed or replaced without affecting the shaft itself. The particular embodiment of my invention illustrated in the drawing is an agitator and feeding device adapted to be mounted in a so-called "dusting box" from which flour is sprinkled or dusted on dough or machinery in bakeries; and it will be 35 seen that my invention permits the agitator and feeding device to be taken out at will without the use of tools of any kind and without disturbing or even disconnecting the shaft. The invention may therefore be said 40 to be particularly applicable to situations in which quick and easy detachment of a part from a supporting shaft, without requiring the use of tools, is desired.

While I have illustrated and described 50 with particularity only a single preferred form of my invention, with a slight modification, I do not desire to be limited to the exact structural details thus illustrated and described; but intend to cover all forms and 55 arrangements which come within the terms employed in the definitions of my invention constituting the appended claims.

I claim:

1. In combination, a member having two 60 separated co-axial open seats and lugs beside and projecting above the seats, the lugs adjacent to each seat being undercut on the side facing the other seat, a shaft adapted to fit into said seats and having in 65 one side notches spaced apart a distance

approximately equal to said seats, and a locking element comprising a leaf spring having at the ends heads adapted to fit into the notches in the shaft and into the opposed undercut portions of the lugs. 70

2. In combination, a member having two separated co-axial open seats and lugs beside and projecting above the seats, the lugs adjacent to each seat being undercut on the side facing the other seat, a shaft adapted to fit into said seats and having in one side notches spaced apart a distance approximately equal to said seats, a locking element comprising a leaf spring having at the ends heads adapted to fit into the notches in the shaft and into the opposed undercut portions of the lugs, and a clip 75 attached to the middle of a said locking element and adapted to grip said shaft when the parts are assembled and the locking element is in its locking position. 80

3. In combination a frame having at opposite ends coaxial separated open seats and lugs on opposite sides of and projecting above each seat, the lugs at both ends of the frame being undercut on the inner side, a shaft adapted to rest in said seats and having in one side notches spaced apart a distance approximately equal to the length of the frame, and a locking element approximately as long as the frame and having at the ends heads each adapted to engage in one of the notches in the shaft and simultaneously engage with the undercut portions of the lugs at one end of the frame. 90

4. In combination, a shaft, a member having separated open seats partially surrounding the shaft, said member having undercut lugs projecting therefrom beside said seats, said shaft having flattened portions adjacent to said lugs, and a locking device having at the ends keys fitting over said flattened portions of the shaft and under said undercut lugs. 100

5. In combination, a shaft, a member having separated open seats partially surrounding the shaft, said member having undercut lugs projecting therefrom on opposite sides of said seats, the shaft having flattened portions at said seats and a locking element of a length to fit between and interlock with the two sets of lugs, the ends of said element being shaped to bear on said flattened portions of the shaft when in locking position and prevent relative rotation between the shaft and said member. 115

6. In combination, a shaft, a member having a seat partially surrounding the shaft, said shaft having flattened portions, separated lugs projecting from said members adjacent to said flattened portions of the shaft, and having shoulders overhanging said flattened portions, and a locking ele- 125 130

ment having parts underlying said shoulders and engaging herewith and with said flattened portions.

7. In combination, a member having two separated coaxial open seats and lugs beside and projecting above said seats, the lugs adjacent to each seat being undercut on the side facing the other seat, a shaft adapted to rest in said seat, and a locking member adapted to extend between said seats and fit at its ends into the undercut portions of said lugs.

8. In combination, a member having two separated coaxial open seats and lugs beside and projecting above said seats, the lugs adjacent to each seat being undercut on the side facing the other seat, a shaft adapted to rest in said seats and having transverse notches in one side spaced apart a distance equal to the distance between said seats, and a locking element of a length to extend between said seats, said locking

element having at the ends keys each adapted to fit into one of the notches in the shaft and into the undercut portions of the adjacent lugs. 25

9. A locking element comprising a strip of spring metal headed at the ends and having a U-shaped spring clip projecting laterally therefrom between the ends. 30

10. A device of the character described, comprising a rectangular frame having aligned open seats at the middle of the ends thereof, lugs beside said seats and undercut on the inner sides, a shaft resting in said seats, a locking device extending lengthwise of the frame and fitting at its ends across said shaft and into the undercut portions of the lugs, ears projecting from the ends of the frame opposite said seats, and a feeding 35 device fastened to said ears. 40

In testimony whereof, I sign this specification.

FREDERICK H. M. HART.
